UNITED STATES PATENT OFFICE.

JOEL JENKINS, OF MONTCLAIR, NEW JERSEY.

SAFETY-PIN.

SPECIFICATION forming part of Letters Patent No. 378,318, dated February 21, 1888.

Application filed October 6, 1887. Serial No. 251,587. (No model.)

To all whom it may concern:

Be it known that I, JOEL JENKINS, of Montclair, in the county of Essex and State of New Jersey, have invented a new and useful Improvement in Safety-Pins; and I do hereby declare that the following is a full and exact description thereof, reference being had to the accompanying drawings, and to the letters of reference marked thereon, making a part of this specification, in which—

Figure 1 is an elevation of my improved re-enforced safety-pin; Fig. 2, a transverse section in line *xx* of Fig. 1; Fig. 3, an elevation of the pin when provided with a guard for the shield in combination with the re-enforcing sleeve; Fig. 4, an elevation of a safety-pin, illustrating the combination therewith of a re-enforcing sleeve made integral with the shield and its guard, Fig. 5 being a plan of the blank from which the shield, sleeve, and guard are struck up, and Fig. 6 a side elevation of the blank when bent and drawn into shape to apply to the pin.

In the use of a safety-pin for uniting and confining two separate pieces of fabric it often occurs that a strain upon the pieces of fabric tending to pull them apart will, by means of the strain thereby created upon the two ends of the pin, so far bend the bar of the pin as to allow the pin-point to become disengaged from the shield, thereby releasing the pin and allowing the fabric to drop therefrom.

The object of my invention is to prevent this disadvantage in the use of the ordinary safety-pin by preventing the bar from yielding under any ordinary strain which may, without tearing, be resisted by the fabric held by the pin.

It consists in the combination of a re-enforcing sleeve formed or fitted upon the bar with a guard made to project from the sleeve toward the outer end of the shield of the pin and in front thereof.

In the accompanying drawings, A represents the bar of a safety-pin; B, its spring-coil; C, the pin and point, and D the shield under which the point is caught and protected.

E represents a re-enforcing sleeve of sheet metal encircling the entire length of the bar from the shield to the spring-coil. This re-enforcing sleeve is simply made of a piece of sheet metal bent and closed about the bar to

clamp the same closely and thereby strengthen it. The tubular form of the sleeve imparts thereto the maximum of strength with the minimum of weight, and the bar re-enforced thereby will resist a very severe deflecting strain, so that where the strain is brought to bear thereon by means of any ordinary fabric held by the pin the fabric will yield before the bar will bend. The point of the pin is thus kept securely within the shield, so as not to become unfastened under any ordinary strain or tension.

To still further guard against a flexure of the bar, a guard-piece, F, may be formed integral with the sleeve E at its inner end, to project radially therefrom immediately in front of the end of the shield, as shown in Fig. 3. I also contemplate making the re-enforcing sleeve in one piece with the shield and guard, as shown in Figs. 4 and 6. In this case a blank of sheet metal is cut in substantially the form shown in Fig. 5, a long narrow strip, *l*, being left for the sleeve, a lateral offset, *m*, for the guard, and opposite terminal offsets, *n n*, for the lips of the shield.

The blank is folded longitudinally in the middle, and its lip end is bent and simultaneously drawn so as to form the shield, as shown in Fig. 6, the lateral offset *m* being left projecting radially from the body of the piece in front of the ends of the lips *n n* of the shield. The bar of the pin is then inserted into the folded blank with its bent end within the U-shaped portion thereof, and the blank is closed and clamped upon the bar and its bend, so as to be firmly united thereto. In being closed about the bar the portion *l* of the blank assumes a tubular form, (see Fig. 6,) and constitutes the re-enforcing sleeve E of the finished device, and the portion *n n* forms the customary shield, while the part *m* projects, as a guard, F, in front of the end of the shield, to prevent the fabric held by the pin from resting against or straining upon the end of the shield, and, in combination with the lips *n n* of the shield, to prevent the pin passing directly through from side to side under the shield.

I do not herein claim the combination of a guard, F, with the shield of a safety-pin, as I have made this feature of my invention the subject-matter of a separate application for Let-

ters Patent now pending, Serial No. 251,586.
I claim as my invention—

1. The combination, with the bar and shield of a safety-pin, of a re-enforcing sleeve enclosing the bar, having a guard-piece formed integrally therewith to project radially therefrom in front of the shield, substantially in the manner and for the purpose herein set forth.
- 10 2. The combination, with the bar of a safety-pin, of a re-enforcing sleeve, a shield, and a guard, all formed in one piece and clamped

upon said bar, to encircle the same and complete and re-enforce the pin, substantially in the manner and for the purpose herein set forth.

In testimony whereof I have signed my name to this specification in the presence of two subscribing witnesses.

JOEL JENKINS.
